CLASP

Filed Sept. 28, 1927

INVENTOR
CHARLES E. HEITKEMPER
BY C. F. Blaue ATTY.

UNITED STATES PATENT OFFICE.

CHARLES E. HEITKEMPER, OF PORTLAND, OREGON.

CLASP.

Application filed September 28, 1927. Serial No. 222,670.

My invention relates to clasps in general, and particularly the necklace clasps, the object being to provide in such a clasp a ring relatively stationary with the adjacent bead, 5 thereby rendering the clasping of the necklace more easily and conveniently accomplished. I accomplish this object by means of the construction illustrated in the accompanying drawing, which is a part of this 10 application for Letters Patent, like characters of reference indicating like parts throughout the several views thereof, and in which,—

Fig. 1 is a sectional view of a necklace 15 end with my invention applied thereto.

Fig. 2 is a view similar to Fig. 1, but showing my invention applied to hollow beads.

Fig. 3 is a section upon line 3—3 of Fig. 1.

20 Fig. 4 is a side elevation of my invention upon an enlarged scale.

Fig. 5 is a plan view of the subject matter of Fig. 4.

Fig. 6 is an end elevation of the subject 25 matter of Fig. 5.

Fig. 7 illustrates a modified form of my invention.

Fig. 8 illustrates a further modification of the same.

30 In general my invention consists of a ring with an extension integral therewith and adapted for insertion within the bead adjacent the clasp, and means upon said stem for passing a cord therethrough.

35 In its preferred form the stem 9 is provided with twin channels 10 oppositely disposed upon the stem and extending the entire length thereof, and being sufficiently large to receive the cord upon which the

40 necklace beads are strung. The ring 11 is rigidly integral with the stem 9, and at the juncture of the stem and said ring I provide a notch 12 as shown in detail in Fig. 5, to receive the cord as it turns upon itself at the 45 ring 11. The split ring 13 of the clasp engages the ring 11 in the usual manner.

The result of this construction is that the ring 11 remains in fixed relationship with the adjacent bead, that relationship being 50 such that the engagement of the ring with the split ring 13 is most easily accomplished,

while with ordinary construction as usually followed in commerce the ring 11 falls back upon the adjacent bead and thereby renders clasping the ends of the necklace difficult. 55

The stem 9 may be cut short of the diametrical length of the bead, as shown in Fig. 1, or when hollow beads are being strung it may be left to project into the second bead, as shown in Fig. 2. 60

The cord is passed along one of the channels 10, over the notch 12 and along the other channel 10, the cord and the stem then being inserted into the bead as shown in Fig. 3. 65

Other methods of securing the cord to the device may be used, as for example the modification shown in Fig. 7, wherein the stem is hollow, and the cord is passed over a transverse pin 15 at the outer end of the 70 hollow stem. A further modification adapted to the use of a single cord is shown in Fig. 8, wherein a hollow stem is provided with a socket 16 adapted to receive a knot in the cord. 75

My invention may be made of any size, and constructed of any materials deemed convenient and suitable for a device of this character, and while I have illustrated a form of my invention found desirable in 80 materializing my invention, I wish to include in this application all mechanical equivalents and substitutes that may fairly be considered to come within the scope and purview of my invention as defined in the 85 appended claim.

Having disclosed my invention so that others may be enabled to construct and to use the same, what I claim as new, and desire to secure by Letters Patent is: 90

In a necklace clasp: a ring; a stem rigidly integral with said ring; twin channels oppositely disposed upon said stem to receive cord; and a notch connecting said channels at the junction of said ring and 95 said stem.

In witness whereof I claim the foregoing as my own I hereunto affix my signature at Portland, county of Multnomah, State of Oregon, this 25th day of May, 1927.

CHARLES E. HEITKEMPER.
